METHOD AND APPARATUS FOR RADIUM
COATING MECHANISM

Harwood B. Fowler, Wayne, Pa.

Application June 16, 1942, Serial No. 447,238

12 Claims. (Cl. 101—123)

My invention relates to apparatus and processes for screen printing, particularly with radium compound.

A purpose of my invention is to mount a printing screen and screen frame on an accurate hinge, desirably a needle bearing hinge, and preferably to provide frictional adjustment at the hinge, counterweighing to oppose the friction, and setting adjustable limit of opening of the hinge.

A further purpose is to place a sliding cover plate over a printing screen frame, to extend the handle of a squeegee through the cover plate, and to move the cover plate back and forth with the squeegee.

A further purpose is to make the slidable cover plate of a printing screen frame removable from the frame.

A further purpose is to construct the sloping face of a squeegee toward the direction of printing motion so as to roll the printing ink or paste through the screen, the angle between such forward face and the screen being between 30 and 36 degrees.

A further purpose is to slope the end of a squeegee handle downwardly so as to improve the control possible over the squeegee.

A further purpose is to hold the object to be screen printed by suction, desirably supplemented by a jig having registry pins, and, preferably, eject the work mechanically against the suction.

A further purpose is to limit the copper sheet of a composite screen and sheet so that the sheet does not touch the frame to which the screen is to be soldered and therefore does not by high heat conductivity weaken the laminating solder during soldering of the screen to the frame.

Further purposes appear in the specification and in the claims.

Figure 1 is a perspective view of a device illustrating the present invention and the cabinet with which it will preferably be used.

Figure 2 is a perspective view of the screen printing device itself.

Figure 3 is a fragmentary perspective of the squeegee.

Figure 4 is a perspective view of the cover plate and guard washer.

Figure 5 is a side elevation of the device.

Figure 6 is a section of Figure 5 on the line 6—6.

Figure 7 is a top plan view of the jig.

Figure 8 shows a typical screen-printed dial in top plan view.

Figure 9 is a fragmentary section of Figure 2 on the line 9—9.

In the drawings like numerals refer to like parts.

This application is related in subject matter to my copending application for Metallic printing screen, Serial No. 437,543, filed April 3, 1942, which application is incorporated herein by reference and made a part hereof.

For certain types of printing, especially on metals or on ceramics, it is desirable to use a screen, often a silk screen. Recently there has been considerable demand for luminous dials for aircraft instruments and the like. Prior to my invention these are believed to have been made entirely by hand. Such dials present a serious problem from the standpoint of printings, since the particles should be relatively coarse in order to give best luminescence and the build-up or deposit on the work should be quite thick. I have succeeded in constructing such luminous dials by screen printing.

A serious problem in making luminous dials is presented by the fact that radium is very dangerous to the workers who handle it. I have succeeded in rendering the operation quite safe if proper precautions be observed. When I refer herein to "radium" I mean any luminous dial material, whether or not it be actually radium.

I preferably print through a composite metallic screen 20 (Figure 6) which consists of a screen 30 wire 21 suitably of stainless steel (preferably 18 percent chromium, 8 percent nickel) soldered at 22 to a sheet 23, preferably of copper. The design is etched at 24 through the metallic sheet and solder. The making and etching of this composite screen is described in detail in my copending application above referred to.

The complete screen 20 is mounted on the bottom of a metallic frame 25, preferably by soldering at 26. In order to prevent the soldering of the frame from melting the laminating solder at 22, due to the high conductivity of copper sheet 23, the copper sheet is terminated at 27, beyond the edge of the design, and not carried out as far as the substantial rectangular frame 25. Solder 45 masks the screen beyond the sheet 23.

In printing position the metallic sheet 23 is down against the work 28, and the screen is above it and spaced by it from the work. As also explained in my copending application, the thickness of the sheet 23 determines the thickness of build-up when radium is forced through the screen in the design areas by a squeegee 29 moving longitudinally in the space inside the frame 25. This will be understood when it is considered that the screen in the design areas can get no

closer to the work than the thickness of sheet 23 permits.

The frame 25 is supported by beams 30 and 31 which have bearing openings 32 engaging conical ends 33 of a needle 34. The needle is rigidly supported by brackets 35 mounted on a base 36 having legs 37. The beams are cross braced at 38 so that the screen will not sway laterally and will register perfectly with the work. Beam 31 is extended at 39 to carry a counterweight 40 adjustable along the beam by releasing a set screw 41. Beam 31 is also provided with an adjustable stop 42 which engages an anvil 43 on the base to prevent too wide opening of the screen. Friction at the needle hinge bearing is adjusted by tightening bolt 44 which extends between beams 30 and 31.

It is necessary to lift the screen frame far enough to give clearance for removal of the finished work. (See Figure 5.) At the same time the angle to which the screen frame is lifted for clearance must not be so great as to cause the radium compound to shift unduly to the left end of the screen frame. Both of these conditions are met by placing the needle bearing well to the rear (left) of the screen frame giving the low angle of lift shown in dot and dash.

The work is positioned beneath the screen in jig 45 mounted on the base and having a suitable (here a circular) depression 46 provided with registry pins 47 and 48 to engage with the holes 49 and 50 in the work.

An opening 51 in the jig connects a source of suction 52 with the bottom of the work so as to hold the work down when the screen is raised after each printing. The source of suction is connected with the opening 51 by a tube 53, and it discharges through a tube 54 into an exhaust fan 55. The fan is located within a discharge opening 56 of a hood 57 having a transparent cover 58 and a side working opening 59 (Figure 1).

When the screen has been opened, the work is raised from the jig by an ejector 60 operated manually in an opening 61 of the jig by a lever 62 pivoted at 63 on the bottom of the base.

Above each beam 30 or 31 is an angle bar 64 or 65, hinged to the beam at 66 or 67. They are united together at 68 and 69, and latched in closed position at 70 by spring latches 71. The spring latches are pivoted at 72 and enter openings 73 (Figure 9).

Between the beam 30 or 31 and the angle bar 64 or 65 is a space 74 in which a cover 75, suitably of transparent plastic, is free to move backward or forward while fully covering the frame 25 in all positions of movement. The length of the cover 75 is great enough to cover the frame 25 in both extreme positions, but is less than the distance between cross members 68 and 69 so that it can move the distance of travel of the squeegee. The cover 75 can be removed readily by releasing the latch 70, and moving the angle bars away from the beams at the free ends of the angle bars.

An elongated opening 76, suitably centrally located, extends through the cover 76, and the handle 77 of squeegee 29 is carried through this opening. A guard washer 78 suitably of transparent plastic, closely fits the handle and covers the elongated opening 76.

The squeegee is preferably of chloroprene, but it may be suitably of rubber or other rubber-like material. It extends over the width of the design, or slightly more, with a forward sloping operating edge 79 whose angle is rather important. This edge must produce a rolling action on the

radium, and not a forcing or packing action as in previous screen printing.

The rear face 80 of the squeegee will preferably be vertical with respect to the screen in operation, as will be the upper forward face 81. But the forward sloping edge 79 should maintain an angle of approximately 33° with the screen when the squeegee is making its printing stroke in order to get best results on radium printing. Good results will be assured if this angle is between 30° and 36°.

The squeegee blade is held between two metallic plates 82 and 83, the plate 83 forming part of an angle 84 secured to the end of the handle 77. The handle extends through the cover plate and is then bent at about right angles (practically horizontal) at 85. Near the grip 86 the handle is bent down at 87, and this latter bend is found to assure better control of the squeegee.

In operation, the screen is raised, a piece of work is placed in the jig, registered by the pins, and gripped by the suction. The screen is then lowered upon the work. Radium paste is placed on the upper face of the screen, the angle bars being raised and the cover plate and squeegee removed to permit access to the top (non-printing face) of the screen.

For the printing operation the squeegee and cover plate are replaced and the angle bars are latched in down position. The squeegee is moved forward in engagement with the radium and with the screen, is lifted and moved back out of contact with the screen and is again moved forward in contact with the screen, the operation being repeated, forward and back until a uniform printing distribution has been obtained over the design. Then the screen is raised and the work is lifted by the ejector and manually removed. A new work piece can then be substituted and the cycle repeated.

In all these operations, a strong exhaust should be maintained in the hood to withdraw dangerous radium emanation and keep it away from the operator. The cover plate prevents too rapid escape of emanation from the radium and also protects the lacquer contained in the radium paste from drying too rapidly.

The radium paste is quite viscous, and must be kept so in order to be screen printed. It probably has a viscosity about like S. A. E. 120 oil, very similar to "molasses in January."

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention what I claim as new and desire to secure by Letters Patent is:

1. In apparatus for screen printing, a screen, a frame supporting the screen and hinge means supporting the frame upon a horizontal axis to shift in vertical planes, a squeegee on the screen, adapted to print through the screen in one position thereof and having a handle, and means for closing the top of the frame during movement of the squeegee to print through the screen.

2. In apparatus for screen printing, a screen, a frame supporting the screen, a cover over the frame having a cover opening, a squeegee having a handle extending through the opening and

means for guiding the cover to permit it to move with the squeegee.

3. In apparatus for screen painting, a screen, a frame for the screen, a squeegee on the screen adapted to print through the screen and having a handle, and means for closing the top of the frame during movement of the squeegee to print through the screen.

4. In screen printing apparatus, a screen, a frame positioning the screen, a squeegee in contact with the upper surface of the screen and having a handle, a transparent cover for the frame having an opening through which the handle passes, and releasable guides for the cover permitting it to move with the squeegee.

5. In a screen printing apparatus, a screen, a frame for the screen, a needle bearing pivotally supporting the frame adjacent to but inwardly of the ends of the frame, a counter weight secured to the frame on the opposite side of the needle bearing from the screen and means for adjusting the friction in the needle bearing comprising means for adjusting the ends of the frame relative to said bearing.

6. In a screen printing apparatus, a screen, a frame for the screen adapted to open and close the screen, a needle bearing pivotally supporting the frame, adjacent to but inwardly of the ends of the frame, a rod secured to the frame on the opposite side of the needle bearing from the screen, a counterweight on the rod and adjustable means mounted on the rod for limiting the opening movement of the screen to a point at which the counterweight holds the frame and screen in a raised position enough to enable the operator to use both hands for removing and replacing articles to be stencilled through the screen.

7. A screen printing squeegee of resiliently deformable material having a sloping forward face and making an angle with the screen during printing which is between 30 and 36 degrees.

8. A screen printing squeegee of resiliently deformable material having a sloping forward face and making an angle with the screen during printing which is about 33 degrees.

5 9. In a screen printing apparatus, a composite screen having a metallic screen wire and a copper sheet laminated by solder to the screen wire, in combination with a metallic frame and solder uniting the screen wire to the frame, the 10 copper being restricted in area and not reaching as far as the frame.

10 15. The process of radium printing, which comprises rolling radium paste through a screen by a sloping resiliently deformable surface making an angle of between 30° and 36° with the screen.

15 20. An apparatus as recited in claim 2, in which the cover opening is an elongated slot in which the handle has limited motion relative to the 20 cover, and a device overlying and contacting said cover and movable with said handle to cover said slot in different positions of relative adjustment of the handle and cover.

20 25. 12. In radium printing, a hood for printing with radium through a stencil screen, said hood comprising a supporting plate, a rear wall, a cover in part at least transparent and engaging the rear wall, end walls supporting the cover relative to the plate, means disposed in the space 30 defined by the forward edges of the end walls, cover and plate to reduce the open area thereof to form a restricted opening through which the operator's hands and an intake air supply can enter the hood, a radium stencilling device 35 disposed inwardly of the hood in the path of air entering said restricted opening, an exhaust channel communicating with the hood toward the rear thereof, and means for generating suction in said exhaust channel to draw air over 40 said stencilling device and into said exhaust channel.

HARWOOD B. FOWLER.
